UNITED STATES PATENT OFFICE.

OWEN DAVID LUCAS AND ERNEST LAWSON LOMAX, OF WESTMINSTER, LONDON, ENGLAND, ASSIGNORS TO V. L. OIL PROCESSES LIMITED, OF WESTMINSTER, ENGLAND, A BRITISH COMPANY.

CRACKING OF LIQUID HYDROCARBONS.

Application filed July 23, 1925, Serial No. 45,525, and in Great Britain December 9, 1924.

This invention relates to the cracking, in the liquid phase, of the heavier hydrocarbons with the object of producing lighter hydrocarbons and its chief object is to increase the 5 yield of the lighter hydrocarbons as compared with processes at present in use.

It has been proposed in processes of this type to heat the hydrocarbons or oils to be cracked to the necessary temperature under 10 pressure, preferably in a pipe still, and to pass the heated liquid into a reaction chamber which is not necessarily further heated but is maintained at the full pressure and protected against loss of heat. From this 15 chamber the hydrocarbon passes through a suitable relief valve into an expansion chamber, after which it is fractionally condensed. Under these conditions a conversion in one 20 operation of the order of 40 per cent may be obtained, but after the lighter oils are removed the heavier portion may be returned through the process and a further conversion obtained.

We have found that the reason for 25 the limitation of the percentage of converted hydrocarbons obtainable in a single operation is the reduction of the conversion rate by the increasing concentration of the lighter oils, produced by the cracking, in the residues. We have further found that the rate 30 of cracking is effected by the difference in temperature between the incoming oil and the oil contained in the reaction chamber, that is to say, the larger the difference of 35 temperature the greater the velocity of the reaction, but this velocity again diminishes as the concentration of the lighter spirit in the heavier oil increases.

According to this invention the lighter 40 hydrocarbons or oils are removed from the conversion or cracking chamber in a continuous manner as they are formed, under conditions of temperature and pressure which enable the cracking reaction to proceed 45 in the body of heavier oils which is therefore free from such proportion of the lighter oils already produced by the cracking operation as would materially reduce the efficiency of the reaction. In the preferred process the lighter oils, together with 50 any permanent gases that are obtained, are drawn off in vapour form into a vapour pressure or refluxing chamber maintaining a temperature substantially below the temper-

ature of the conversion chamber, but sufficiently high to prevent, under the pressure employed (that of the conversion chamber), the condensation of any oils below a predetermined density, while heavier oils which may be carried over are condensed in the refluxing chamber and then pass through a reflux cooler leading the oils condensed back into the conversion chamber for further treatment.

Fresh oil is admitted to the conversion 65 chamber with or independently of the returned oils and the entering oil may be pre-heated to a temperature substantially below the cracking temperature, in which case it may be sprayed or allowed to drop upon the 70 upper surface of the oils undergoing cracking; or it may be admitted, with or without the refluxed oils, to the lower part of the conversion chamber to pass into the body of heavier oils, in which case the preheating may 75 be carried up to the cracking temperature to supply the heat to the conversion chamber, which then may require no external heating but may be merely lagged to avoid loss.

In order that the said invention may be 80 clearly understood and readily carried into effect, the same will now be described more fully with reference to the accompanying diagram, which illustrates the general arrangement of a plant adapted to carry out 85 the present process. The individual pieces of apparatus employed are of known type and are not shown in a constructional form.

A is the oil feed tank from which the oil passes through the non-return valve *a* to the 90 pressure pump *a*¹. B is a pipe still in which the oil is heated. C is the cracking or conversion chamber. D is the refluxing chamber 95 and E is the reflux cooler connected to the chamber C at one side and to the conversion chamber at the other side. F is a rectification column, G an expansion chamber, H a residue cooler and J, J fuel oil receivers. K is a heat exchanger. L indicates a vapour refining plant. M is a main condenser for the 100 light oils, N a gas separator, O, O light oil receivers and P a gas holder.

The oil from the feed tank is pumped by 105 the pressure pump *a*¹ through the heat exchanger K and thence through the pipe still B which is heated by gas from the gas holder P or direct from the gas separating end of

the plant or by oil from the fuel tank R. The oil passes from the pump through the valve a^2 to the heat exchanger K and from this through the valve k to the pipe still, the 5 still comprising the coil b connected to the inlet pipe b^1 and the outlet pipe b^2 . The heated oil passes through the pipe b^2 to the conversion or cracking chamber C, which is preferably merely lagged and is not separately heated, the pipe still heating the oil 10 sufficiently for the re-action in the conversion chamber. When the oil in the conversion chamber reaches the necessary temperature the process may be carried on by pumping the fresh oil into the chamber 15 through the pipe c with valves c^1 and c^2 , into the top of the chamber C so that the oil drops on top of the heated body of oil in the chamber; or the oil may continue to 20 be passed through the body of oil in the conversion chamber, entering at the bottom.

It will be seen that there are two alternative methods of feeding the fresh oil to the conversion chamber C, one in which the 25 oil is preheated to a temperature somewhat above that in the conversion chamber by passing it through the heat exchanger K and still B on its way to the said chamber, and the other in which the valves a^2 and k are closed and the fresh oil is pumped 30 through the valves c^1 and c^2 to meet the refluxed oil (as hereinafter described) and enters the conversion chamber at a relatively low temperature. In the latter case the 35 necessary heat for the conversion chamber is obtained by circulating the oil from it through the still B by means of the pump c^4 , the oil being heated in the still to a temperature above that in the conversion chamber 40 itself, the fresh and refluxed oil maintaining the chamber at the correct temperature. The heat exchanger K is not employed in this method of supply. The general process is however the same in either 45 method of supplying the fresh oil.

The refluxing chamber D into which the vapours and gases pass from the conversion chamber C is connected through a relief valve d , set to operate at the maximum pressure desired for cracking, to the expansion chamber G into which the light cracked oils and gases pass through the said valve, this 50 chamber being maintained at a relatively low temperature and connected by the tube g to the dephlegmator or rectification column F. A portion of the vapours passing into the chamber D is condensed and returned to the conversion chamber C through the cooler E, so as to drop upon the upper surface of the 55 oils in the chamber C. The heavy oil from the chamber C leaves through the valve c^5 . The heavier portions of the light oils carried over in vapour form from the refluxing chamber D are condensed both in the expansion chamber G and in the column F and the con-

densed oils in the expansion chamber and in the lower part of the column are carried through pipes g^1 and f to the fuel oil receivers J, the hot oil from the rectifying column passing first through the heat exchanger K, around the coil, while the fuel from the expansion chamber passes through the residue cooler H. The fuel or heavy oils so removed can be taken for further cracking treatment. The oils in the conversion 70 chamber C may pass in part through the relief valve c^3 and circulating pump c^4 back to the inlet tube b^1 of the pipe still for heat 75 circulating purposes, while part may pass through the second relief valve c^5 to the feed end of the plant behind the pressure pump a^1 only if it is desired to mix a portion of partly cracked oil with the fresh oil for further treatment. The gas and light oils 80 are withdrawn from the top of the rectifying column F, which is provided with a water cooling coil f^1 at the upper end, through the outlet pipe f^2 and valve f^3 to the vapour refining plant L, thence through the pipe l and valve l^1 to the main condenser M from 85 which the light oils pass to the gas separator N, the gases from which pass through the relief valve n set at a pressure say of about 50 lbs. per square inch, to the gas holder P or in part to the pipe still for heating purposes. The refining operation carried out in the plant L may be of known type such as the passing of the oils over bauxite, fuller's earth, or like filtering material. The light oils from the condenser M 90 after passing through the gas separator are received by the receivers O.

The vapours from the conversion chamber C pass directly into the refluxing chamber D situated immediately above the chamber C and as this refluxing chamber D is maintained at any desired temperature below that of the conversion or cracking chamber light oils whose boiling point is below any given level, for example 200° C., pass away 100 as vapour to the expansion chamber, while oils whose boiling point is above this level pass first into the reflux cooler E in which they are cooled before re-entering the conversion chamber with the fresh oil. The 105 temperature in the refluxing chamber is critical for any given range of light oils. It is well understood that as the pressure on an oil mixture rises the boiling point rises rapidly but the boiling point of the lighter portions rises more rapidly than that of the heavier portions so that the difference between the boiling points is reduced by the pressure. The refluxing temperature therefore must be maintained constant within 110 narrow limits.

The oil from the conversion chamber C is taken through the pipe c^6 and relief valve c^7 from a level in the chamber situated at a suitable distance above the lower end, the oil 115

so removed passing through the coil f^4 in the lower end of the rectification column F so as to heat the lower end of this column to any desired temperature, the oils then 5 passing through the expansion valve g^2 to the expansion chamber G which is provided with a relief valve g^3 . The oils taken direct from the conversion chamber into the expansion chamber in this manner contain 10 both light and heavy ingredients which are separated in the expansion chamber and in the rectification column to which the vapours are led from the expansion chamber as already mentioned.

15 The temperatures and pressure employed will vary to some extent according to the nature of the oils under treatment, but the approximate temperatures and pressures are as follows:—In the conversion chamber C 20 a temperature of 450° to 550° C. with a pressure of about 600 to 1,000 lbs. per square inch would be employed. The fresh oil would be preheated, if supplied through the still B, to a temperature between 500° and 25 600° C. to maintain the conversion chamber at the above temperature, while if admitted directly to the conversion chamber no pre-heating is required and the circulation through the pump c^4 and the still is regulated 30 to maintain the conversion chamber temperature between 450° and 550° C., allowing for the admission of the cold oil. The pump supplying the fresh oil would operate at about 600 to 1,000 lbs. per square inch, 35 corresponding to the pressure in the conversion chamber. The refluxing chamber D into which the vapours of the cracked oils pass would be heated to a temperature above 200° C. and usually to say about 360° to 40 400° C. and its pressure, of course, would be that of the conversion chamber with which it is in communication, preferably through apertures in a tubular extension of the latter chamber projecting through the bottom of 45 the refluxing chamber towards the upper end, the reflux cooler E for the returned oils being connected to the bottom of the chamber D. The relief valve between the chamber D and the expansion chamber G would 50 be set to open at about 600 lbs. or higher according to the pressure in the chamber C and the expansion chamber G is maintained at a pressure of about 75 lbs. and a temperature of approximately 350° C. The pressure in the dephlegmator or rectification column 55 F may be about 75 lbs. and the expansion chamber G is connected to the column F through the valves g^4 set to open at about 75 lbs. The outlet for the gas and spirit 60 from the column F is valve controlled by the relief valve f^3 opening at about 25 lbs. pressure.

The condensed oil in the expansion chamber is allowed to collect in this chamber and 65 passes to the outlet, which may lead to the heavy oil tank, through a relief valve set at about 75 lbs. The coil f^4 connected to the conversion chamber and placed in the lower part of the rectification column is connected through the relief valve 70 g^2 (set to open at about the pressure in the conversion chamber) to a pipe opening into the expansion chamber G some distance above the bottom so that heavy oils from the conversion chamber pass through 75 the coil under pressure, which supplies heat to the condensed oils in the rectification column, and thence into the bottom of the expansion chamber and subsequently to the 80 heavy oil tank.

The heating of the conversion chamber, if desired, may be effected either externally or internally, by burning oil or gas produced in the cracking process or other suitable fuel, by electrical means, or by superheated steam or vapour. Or as described above with reference to the diagram the preheating of the oil itself may be sufficient to maintain the temperature required in the conversion chamber, which is in this case protected 85 against loss of heat.

The temperature of the refluxing chamber is adjusted to a point which is below the critical temperature corresponding with the pressure for the lightest oil which it is 90 not desired to remove in a state of vapour, so that the lower the maximum boiling point required for the cracked oil the lower will be the temperature of the refluxing system. With the temperatures and pressures 95 given above, in which the refluxing system is maintained between 350° and 400° C. with a pressure of 800 lbs. the end boiling point of the light oils would be about 200° C. 100

While the temperatures and pressures indicated above are suitable for various oils the following example may be given of the treatment of a particular oil (Baku Mazout of specific gravity 0.901) as carried out:—

Temperature of reaction or conversion 110 chamber 525° C. under a pressure of 800 lbs. Temperature of the refluxing chamber 365° C. at, of course, the same pressure. The treatment resulted in a conversion to light spirit (specific gravity 0.739 and boiling point up to 200° C.) of 47 per cent of the heavy oil treated. The gas produced amounted to 13.3 per cent and a residue of 115 39 per cent was left having a specific gravity of 0.924. 120

What we claim and desire to secure by Letters Patent of the United States is:—

1. A process for the production of light from heavy oils which consists in heating the oils rapidly to the cracking temperature 125 in a tube still, passing the heated oils into a conversion chamber in which they are maintained in bulk at the cracking temperature and at a pressure of from 600 to 1,000 lbs. per square inch, drawing off the lighter 130

- oils in vapour form into a vapour pressure or refluxing chamber open directly to and forming an extension of the conversion chamber and consequently at the same pressure of 600 to 1,000 lbs. per square inch, maintaining the said refluxing chamber at a temperature substantially below that of the conversion chamber, but sufficiently high to prevent, under the said pressure common to the conversion and refluxing chambers, the condensation of any oils below a predetermined density, condensing the heavier oils in the aforesaid refluxing chamber and then passing the condensed oils without reheating and below the cracking temperature through a branch passage directly back into the conversion chamber for further treatment, simultaneously drawing off liquid oils from the conversion chamber, releasing the said liquid oils through a pressure reducing valve 20 into a lower pressure chamber, and removing the vapour of the lighter oils from the said lower pressure chamber.
2. In a cracking process as in claim 1, 25 passing the oils condensed in the refluxing chamber, prior to their return to the conversion chamber, through a reflux cooler while maintaining them under the pressure in the conversion chamber.
3. In a cracking process as in claim 1, 30 passing the hot liquid oils removed from the conversion chamber through a pipe coil in a rectification chamber for the lighter oils before passing to the said lower pressure chamber.
